T. LONG

FURNACE REGULATOR

Filed May 12, 1927

Thomas Long. INVENTOR
BY
A. G. Burns ATTORNEY

UNITED STATES PATENT OFFICE.

THOMAS LONG, OF SOUTH BEND, INDIANA.

FURNACE REGULATOR.

Application filed May 12, 1927. Serial No. 190,713.

This invention relates to improvements in furnace regulators, and the objects thereof are to provide automatic means for operating the draft and check dampers of a furnace and thereby regulate the fire therein, and to provide in connection with the automatic regulating means a device controlled by the coal door whereby said dampers are automatically closed upon opening of the coal door. Another object is to provide means for adjusting said automatic means from a point remote from the furnace.

These objects are accomplished by the construction illustrated in the accompanying drawings, in which:

Fig. 1 is a diagrammatical view of the invention applied to a furnace of ordinary construction, the view being a side elevation thereof;

Fig. 2 is a similar view showing a front elevation of the same;

Fig. 3 is a side elevation of a thermostatic appliance forming part of the invention, parts being broken away;

Fig. 4 is a fragmentary plan view of the structure shown in Fig. 3, a portion being in section;

Fig. 5 is a front elevation of an actuating lever for the thermostat; and

Fig. 6 is a perspective view of a fulcrum bearing for the actuating lever.

The characters appearing in the description, refer to parts shown in the drawings and designated thereon by corresponding characters.

The invention comprises in combination with a furnace 1 which is provided with a coal door 2, a draft damper 3 and its ash-door 4 and a check damper 5 in its smoke pipe 6, and a thermostatic means having connections with said dampers for their operation.

The thermostat consists of an expansion member 7, preferably in the form of a tube, the tube being positioned in the dome 8 of the furnace, there being a fixture 9 on the forward part of the tube for securing it in place. On the front end of the tube which protrudes from the fixture is mounted a housing 10, the forward end of which is curved and has a vertical disposed opening 11 therein, the bottom of said housing also having an opening 12 therein. An oscillating member 13 extends through the side walls 14 and 15 of the housing in which it is supported, and has a fixed eccentric 16 thereon

between said walls, and an adjusting arm 17 provided with a weight 18 at its outer end, by which arm the eccentric is adjustably turned upon the axis of the oscillating member 16 accordingly as said arm is moved. An actuating lever 19 having a bifurcated head 20 is mounted upon said eccentric, which eccentric extends laterally through said head, and which lever extends through the opening 12 in the housing. A rod 21 extends longitudinally through the expansion member 7, which rod is composed of metal that is less susceptible to expansion when heated than the expansion tube 7, the rear end of the rod being secured to the corresponding end of the tube 7 by a plug 22 in which the rod is threaded. The forward end of the rod projects through the head 20 of the actuating lever and has adjustably secured thereon a fulcrum block 23, which block has wedge shaped bearings 24 that bear respectively in corresponding notches 25 in the front of said head, there being a nut 26 on said rod for adjusting said block. On the forward end of the rod 21 is adjustably secured a bracket 27 upon which is pivotally mounted an indicator hand 28 that protrudes through the slot 11 and has a bent finger 28' that overlaps the curved front face 85 of the housing. Said hand has an upwardly extending slotted arm 29 that is engaged by a stationary pin 30 that projects downwardly from the top of the housing and extends loosely through the slot in said arm, so that when said rod 21 is moved longitudinally through the action of the expansion member 7, the hand 28 is caused to turn upon its pivot more or less accordingly. Likewise the actuating lever 19 is caused to turn upon the eccentric 16 through the medium of the fulcrum block and the rod 21 through the action by the expansion member.

Positioned above the floor is a standard 31 upon which is pivotally mounted an adjusting lever 32 that is connected with the weight 18 on the adjusting arm 17 by means of a cable 33, there being a sector 34 on the standard for securing the lever 32 in adjusted positions. Beneath the floor 30 is secured a hanger 35 in which is pivotally supported a tilting bar 36, one end of which supports a swivel pulley 37, and the opposite end of which is connected with the latch 38 on the coal door 2 by means of a chain 39. The hanger 35 is so located relative to the coal door that when the door is opened, the tilt-

ing bar is permitted to tilt so that the pulley 37 is lowered thereby.

An idler 40 is supported by a post 41 beneath the floor 30 at a point above the check damper 5, and a cable 42-42' is connected at one end with said check damper and is strung over the idler 40 and pulley 37, its opposite end being secured to an arm 43 that projects from the side of the draft damper 3. The cable 42' has also adjustable connection with the actuating lever 19 at the outer end thereof, and is of such length that normally when the check damper 5 is closed, the draft damper 3 will be held ajar, or, as the draft damper 3 is closed, the check damper 5 will be opened more or less accordingly.

In the operation of the invention, as the tube 7 expands under the influence of the heated air in the dome of the furnace, lengthwise movement is imparted thereby to the rod 21 so that the actuating lever 19 is swung upon the eccentric 16, and the cable 42' attached thereto is pulled downwardly, permitting the draft damper 3 to close and causing the check damper to open. In this manner combustion of fuel in the furnace is retarded when the heat in the dome becomes excessive. When the temperature in the dome recedes the tube 7 consequently contracts so that the rod 21 moves forwardly permitting movement of the lever 19 in the opposite direction from that in the previous instant, thus causing the draft damper 3 to open and the check damper 5 to close.

When the coal door 2 is swung open, the bar 36 is relieved, permitting the lever 19 to tilt and lower the pulley 37, causing the cable 42 to slacken, which permits both the draft damper 3 and check damper 5 to close. In this manner when fuel is being supplied to the furnace through its coal door, the suction of the draft in the smoke pipe causes an inrush of air through the coal door which prevents the emission of smoke and fumes from the firebox into the furnace room.

The tendency of the check damper 5 to close is somewhat greater than that of the draft damper, which is due to placing the connection of the cable 42 with the check damper closer to its hinge than the connection of the opposite end 42' of the cable with the draft damper. Or, the check damper may be weighted so as to overbalance the draft damper. In this manner, the tendency is for the check damper to close and the draft damper to open opposed to the expansion of the tube 7.

By raising or lowering the adjusting lever 32, the adjusting arm 17 is raised or lowered and the eccentric 16 is thereby adjusted and the poise of the lever 19 is altered so that the dampers 3 and 5 controlled by the cable

42-42' which is attached to the actuating lever will be influenced accordingly at an earlier or later stage in the expansion of the tube 7. Thus, by positioning the adjusting lever 32 the dampers may be initially set so that the combustion in the furnace will be maintained at the desired rate, and by adjusting the bracket 27 properly on the rod 21, the indicator hand 28 may be set so that its finger 28', by its movement over the curved face of the housing, will indicate the varying conditions of temperature in the dome of the furnace that effect the thermostat.

What I claim is:

1. In combination with a furnace provided with a coal door, draft damper and a check damper, a thermostatic means in connection with said furnace; an oscillating member including an eccentric thereon and an adjusting arm therefor; an adjusting lever remotely located having operative connection with said arm; an actuating lever on said eccentric influenced by said thermostatic means; an indicating member influenced by said thermostatic means; a tilting member including a pivoted bar and pulley supported on one end thereof; a connection between the other end of said bar and the coal door of said furnace whereby said bar is relieved when said door is opened so as to lower said pulley; and a cable extending over said pulley, one end of said cable having connection with said check damper and the other end thereof having connection with said draft damper and being movable so that normally when the check damper is closed the draft damper will be opened, and vice versa, said actuating lever having operative relation with said cable.

2. In combination with a furnace provided with a coal door, draft damper and a check damper, a thermostatic means in connection with said furnace; an oscillating member including an eccentric thereon and an adjusting arm therefor; an adjusting lever remotely located having operative connection with said arm; an actuating lever on said eccentric influenced by said thermostatic means; a tilting member including a pivoted bar and pulley supported on one end thereof; a connection between the other end of said bar and the coal door of said furnace whereby said bar is relieved when said door is opened so as to lower said pulley; and a cable extending over said pulley, one end of said cable having connection with said check damper and the other end thereof having connection with said draft damper and being movable so that normally when the check damper is closed the draft damper will be opened, and vice versa, said actuating lever having operative relation with said cable.

3. In combination with a furnace provided with a coal door, draft damper and a check

damper, a thermostatic means in connection with said furnace; an oscillating member including an eccentric thereon and an adjusting arm therefor; an actuating lever on said eccentric influenced by said thermostatic means; a tilting member including a pivoted bar and pulley supported on one end thereof; a connection between the other end of said bar and the coal door of said furnace where-
5 by said bar is relieved when said door is opened so as to lower said pulley; and a cable extending over said pulley, one end of said cable having connection with said check damper and the other end thereof having connection with said draft damper and being movable so that normally when the check damper is closed the draft damper will be opened, and vice versa, said actuating lever having operative relation with said cable.
10 4. In combination with a furnace having a coal door including a draft damper and check damper, a thermostatic means in connection with said furnace; an adjusting member; an actuating lever supported by said adjusting member influenced by said thermostatic means; a tilting member includ-
15 ing a pulley supported thereby; a cable ex-
tending over said pulley and connecting said check damper and draft damper and being movable so that normally when the check damper is closed the draft damper will be opened, and vice versa, and an operable con-
20 nection between said coal door and tilting member whereby said cable is slackened when said coal door is opened and both the draft damper and check damper are thereby closed.
25 5. In combination with a furnace having a coal door including a draft damper and check damper, a thermostatic means in con-
30

nection with said furnace; an actuating lever influenced by said thermostatic means; a tilting member including a pulley supported thereby; a cable extending over said pulley and connecting said check damper and draft 45 damper and being movable so that normally when the check damper is closed the draft damper will be opened, and vice versa, and an operable connection between said coal door and tilting member whereby said cable 50 is slackened when said coal door is opened and both the draft damper and check damper are thereby closed.

6. In an appliance for controlling the draft damper and check damper of a fur-
nace, a pivotally supported lever member in-
cluding a pulley at one end thereof; a cable
connecting said draft damper and check
damper and extending over said pulley; a
second cable connecting the other end of said
lever and the coal door of the furnace where-
by said lever is actuated when the coal door
is opened or closed; and a thermostatically
controlled mechanism influenced by the heat
generated within the furnace, which mecha-
nism has actuating relation with the first
mentioned cable. 60

7. In an appliance for controlling the draft damper and check damper of a fur-
nace, a pivotally supported lever member in-
cluding a pulley at one end thereof; a cable
connecting said draft damper and check
damper and extending over said pulley; and
a second cable connecting the other end of
said lever and the coal door of the furnace 70
whereby said lever is actuated when the coal
door is opened or closed. 75

In testimony whereof I affix my signature.
